(57) **CLAIM**

The ornamental design for a flexible printed circuit board connector, as shown.

DESCRIPTION

FIG. 1 is a front, to and right side perspective view of a flexible printed circuit board connector, showing our design.

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.
